U.S. Provisional Patent Application Disposable Cup with Fold Down Lid; George E. Sarson et al.; PAT 52192P-2; filed Jul. 17, 2002.

Primary Examiner—M. N. Pandozzi

(74) Attorney, Agent, or Firm—Jenkens & Gilchrist

(57) **CLAIM**

The ornamental design for a cup having inwardly folding lids, as shown.

DESCRIPTION

FIG. 1 is a perspective view of a cup having inwardly folding lids; the lids being shown in an open position.

FIG. 2 is a right-side view of the cup of FIG. 1.

FIG. 3 is a front-side view of the cup of FIG. 1,

FIG. 4 is a left-side view of the cup of FIG. 1.

FIG. 5 is a back-side view of the cup of FIG. 1.

FIG. 6 is a top view of the cup of FIG. 1.

FIG. 7 is a bottom view of the cup of FIG. 1.

FIG. 8 is a perspective view of the cup having inwardly folding lids of FIG. 1; the lids being shown in a closed position.

FIG. 9 is a right-side view of the cup of FIG. 8.

FIG. 10 is a front-side view of the cup of FIG. 8.

FIG. 11 is a left-side view of the cup of FIG. 8.

FIG. 12 is a back-side view of the cup of FIG. 8.

FIG. 13 is a top view of the cup of FIG. 8; and,

FIG. 14 is a bottom view of the cup of FIG. 8.
